CLAIM

I claim the ornamental design for a train station hub for playing Mexican train dominoes, as shown and described.

DESCRIPTION

FIG. 1 is a perspective view of a train station hub for playing Mexican train dominoes, showing my new design;

FIG. 2 is a top plan view thereof;

FIG. 3 is a bottom plan view thereof;

FIG. 4 is a front elevational view thereof, the rear elevational view being a mirror image thereof, and,

FIG. 5 is a left-side elevational view thereof, the right-side elevational view being a mirror image thereof.

The broken lines showing domino playing pieces in FIG. 1 depict environmental matter and form no part of the claimed design.
